UNITED STATES PATENT OFFICE

2,588,447

MOISTURE-ABSORBING SMOKING PIPE

Andrew O. Winden, Madelia, Minn.

Application October 25, 1946, Serial No. 705,756

1 Claim. (Cl. 131—202)

1

This invention relates to smoking pipes, and more particularly to a smoking pipe of the type having means for filtering moisture out of the tobacco smoke as it is drawn through the pipe.

A main object of the invention is to provide a novel and improved smoking pipe of simple construction which provides double filtering action of smoke drawn from the pipe bowl and which is provided with means for removing moisture from the smoke, said means being easy to remove and not being subject to clogging.

A further object of the invention is to provide an improved smoking pipe of the filter type, said pipe being inexpensive to manufacture, easy to clean and neat in appearance.

Further objects and advantages of the invention will become apparent from the following description and claim, and from the accompanying drawings, wherein:

Figure 1 is a side elevational view of a smoking pipe constructed in accordance with the present invention.

Figure 2 is a vertical longitudinal cross-sectional view of the smoking pipe shown in Figure 1.

Figure 3 is a top plan view of the pipe of Figure 1.

Referring to the drawings, 11 designates a pipe according to this invention, said pipe comprising a bowl member 12 having secured thereto a stem member 13. Bowl member 12 is formed with a tobacco-receiving cavity 14 whose lower portion communicates by a horizontal passage 15 with a horizontal bore 16 enlarged in diameter relative to passage 15. Removably positioned in bore 16 is a porous cylindrical wad of material 17 which functions as a filter for tobacco smoke passing through bore 16. A screw-threaded end plug 18 is secured in the end of bore 16 which provides access to said bore for removal and replacement of filter wad 17.

Formed in the rear portion of bowl member 12 is a vertical bore 19 which intersects horizontal bore 16 and in which is positioned a removable porous filter wad 20 similar to wad 17. A screw-threaded end plug 21 secured in the lower end of bore 19 provides access to said bore for removal and replacement of wad 20.

Formed in the upper rear portion of bowl member 12 and communicating with bore 19 is a cylindrical horizontal recess 22 axially aligned with the smoke bore 23 of stem member 13. Recess 22 communicates by a reduced portion 24 with a vertical bore 25 formed in bowl member 12 behind the tobacco-receiving cavity 14. Bore 25 contains a removable absorbent wick 26 which

2

absorbs moisture from tobacco smoke coming in contact therewith. Said moisture collects in the lower portion of bore 25 after wick 26 becomes saturated. A screw-threaded end plug 27 is secured in the top opening of bore 25, said plug 27 being removable for providing access to the bore when wick 26 is to be removed for replacement and when the bore 25 is to be cleaned out.

Stem member 13 is formed with a reduced end 10 28 which is frictionally secured in bore 22. Formed in the inner end portion of stem 13 is an enlarged bore 29 communicating with smoke bore 23. Secured to the inner end of stem member 13 is a sleeve 30 which projects axially through

15 cylindrical recess 22 and reduced bore portion 24 and into vertical bore 25. Sleeve 30 is substantially less in outer diameter than recess 22 and reduced bore portion 24, whereby clearance is provided for smoke to pass forwardly from bore 19 toward wick 26 and into the open end of sleeve 30, the smoke being relieved of moisture by contact with wick 26 and then passing into the open end of sleeve 30 toward chamber 29 and smoke bore 23.

20 25 It will be seen that wads 17 and 20 provide a double filtering action to remove solid particles and a certain amount of moisture from the tobacco smoke, and that any residual moisture in the smoke is removed by absorbent wick 26. The 30 resultant smoke in smoke bore 23 is thus maintained substantially dry and is cooled substantially by its passage through the various bores and passages leading from tobacco cavity 14 to smoke bore 23.

35 While a specific embodiment of a smoke-filtering tobacco pipe has been disclosed in the foregoing description, it will be understood that various modifications within the spirit of the invention may occur to those skilled in the art. There-

40 fore it is intended that no limitations be placed on the invention other than as defined by the scope of the appended claim.

What is claimed is:

45 A smoking pipe adapted for removing moisture and foreign particles from smoke passing therethrough, comprising a bowl member having a tobacco-burning cavity therein, a first bore communicating with said cavity adjacent the bottom thereof and extending horizontally rearward therefrom, a second bore communicating with said first bore at a point remote from said cavity and extending perpendicularly upward therefrom, filtering means within said first and second bores for removing foreign particles out of smoke passing therethrough, a recess communicating with

55

said second bore at a point remote from said first bore and extending in a parallel superimposed relation to the latter, there being a vertical bore in said bowl member adjacent one end of said recess and in communication therewith, an absorbent wick in said vertical bore for removing the moisture from the smoke, an elongated stem member having an axial bore therethrough and adapted to be attached at one end to said bowl member so that said axial bore is in communication with the other end of the recess of said bowl member and co-extensive therewith, and means carried by said stem member and positioned in said recess for reversing the flow of smoke therethrough, whereby when said pipe is in use the smoke is drawn from said tobacco cavity through said first and second bores to the recess and is caused to flow through the latter to said vertical bore and then reversely through

said means carried by said stem member and said axial bore consecutively for discharge.

ANDREW O. WINDEN.
